CHEST OR THE LIKE

John J. Lubberts and Lambert J. Mulder, Grand Rapids,
Mich., assignors to Tomlinson of High Point, High
Point, N. C., a corporation of North Carolina

Application April 8, 1957, Serial No. 45,615

Term of patent 14 years

(Cl. D33—19)

We claim:

The ornamental design for a chest or the like, substantially as shown.
